VISIBLE RECORD LOOSE-LEAF BINDER

Adolph G. Lotter, Milwaukee, Wis., assignor to
Stationers Loose Leaf Company, Milwaukee,
Wis., a corporation of Wisconsin

Application July 9, 1943, Serial No. 493,994

2 Claims. (Cl. 129—17)

This invention relates to loose leaf binders and refers more particularly to the so-called visible record type of binder wherein the complementary hingedly connected binder heads are longitudinally shiftable with respect to each other.

In loose leaf binders of this type each binder head carries a series of impaling prongs to engage in the apertures of the leaves. The relative spacings of the impaling prongs and apertures are such that when the binder is open leaves on the prongs of one binder head may be shifted with relation to the leaves mounted on the prongs of the other binder head by shifting the binder heads longitudinally with respect to each other.

Shifting of the binder heads is effected manually and while it can be done only with the binder open, in the past there was little control over the relative longitudinal positions of the binder heads at the time of closure of the binder by the operator. If the operator was not careful he was apt to close the binder without making certain that the heads were in such relative position of longitudinal adjustment that the prongs would line up properly with the apertures in the leaves. Tearing of the leaves thus often resulted.

It is, therefore, an object of this invention to provide means for automatically effecting end-wise shifting of the binder heads to one or the other of their limits of movement during the closure of the binder to thus insure against tearing the leaves by improper alignment of the prongs and apertures.

More specifically, it is an object of this invention to provide cam means on one of the binder heads cooperating with an abutment on the other binder head by which the binder heads are positively shifted longitudinally to one or the other of their limits of motion during the act of closing the binder.

The heads of binders of this type are generally provided with latch means for holding the same in closed and partially opened positions and these latch means consist of a pivoted latch member on one of the binder heads coacting with a hook on the other binder head.

With a view toward minimizing the number of parts and achieving maximum simplicity, it is another object of this invention to mount the cam by which the desired automatic longitudinal shifting of the binder heads is accomplished on the pivoted latch member to engage the hook during closure of the binder.

With the above and other objects in view which will appear as the description proceeds, this invention resides in the novel construction, com-

bination and arrangement of parts substantially as hereinafter described, and more particularly defined by the appended claims, it being understood that such changes in the precise embodiment of the herein disclosed invention may be made as come within the scope of the claims.

The accompanying drawing illustrates two complete examples of the physical embodiments of the invention constructed in accordance with the best modes so far devised for the practical application of the principles thereof, and in which:

Figure 1 is a perspective view of a loose leaf binder embodying this invention, said view showing the binder in a partially open position;

Figure 2 is a view showing one end portion of the binder heads, said view looking into the interior of the binder heads and showing the same in their fully opened positions;

Figure 3 is a top plan view of one end portion of the binder heads and illustrating specifically the manner in which the cam functions to effect shifting of the heads in the event they are not properly positioned relative to each other for closure; and

Figure 4 is a fragmentary perspective view illustrating another cam arrangement for effecting the desired longitudinal shifting of the binder heads.

Referring now to the accompanying drawing in which like numerals indicate like parts, the numerals 5 and 6 designate two complementary binder heads hingedly connected by means of a hinge 7, the loops 8 and complementary spaces of which are of such relative lengths as to enable a degree of longitudinal shifting of one binder head with respect to the other.

Both of the binder heads are equipped with the covers 9 and sets of impaling prongs 10 spaced to engage in the apertures of the leaves 11 when the binder heads are at one or the other of their limits of longitudinal adjustment.

A latch mechanism is provided for releasably holding the binder heads in closed or partially opened positions. This latch mechanism is similar to that shown and described in Patent No. 1,744,275 issued to Adolph G. Lotter, January 21, 1930. Briefly, it comprises a pivoted latch member 12 and a cooperating hook 13 at each end of one of the binder heads. A rock shaft 14 having crank arms on its opposite ends engaging in arms 15 of the latch members connects the two latch members for simultaneous operation, and springs 16 yieldingly bias the latch members to their operative positions from which they may be retracted by pressure applied on finger pieces 17.

The hooks 13 are provided with two shoulders or abutments 18 and 19 for engagement with the arms 15 of the latch members.

To insure the binder heads being in one or the other of their extreme positions of longitudinal adjustment before the ends of the prongs of one binder head can contact the leaves on the prongs of the other binder head the arm 15 of one of the latch members has a cam 20 mounted thereon in position to engage the end of the cooperating hook 13 during closure of the binder.

As shown in Figures 2 and 3 any relative positioning of the binder heads other than the extremes results in automatic longitudinal shifting of the binder heads to bring them into proper relative relationship during the act of closing the binder. In this manner the desired assurance against tearing the leaves by improper alignment of the prongs with the apertures is entirely eliminated.

Another arrangement of cams to accomplish the same purpose is illustrated in the modified embodiment of the invention shown in Figure 4. In this instance the two wall surfaces 21 of the binder heads adjacent to the hinged connection 7 have complementary cams 22 secured thereon. These cams are so disposed that during closure of the binder the desired longitudinal shifting of the binder heads is effected.

From the foregoing description taken in connection with the accompanying drawing it will be readily apparent to those skilled in the art that this invention provides a substantial improvement in visible record loose leaf binders by positively assuring proper positioning of the binder heads as the binder is closed.

What I claim as my invention is:

1. In a loose leaf binder of the visible record type, wherein the complementary binder heads are connected for relative longitudinal as well as hinged motion so that leaves on the impaling prongs of one binder head may be shifted with respect to leaves on the impaling prongs of the other binder head; latch mechanism for releasably securing the binder heads in their closed positions; said latch mechanism comprising a hook fixed to one of the binder heads, and a pivoted spring biased latch member on the other binder head; and a cam mounted on said latch member and positioned to engage the hook and automatically shift the binder heads longitudinally with respect to each other to one limit of motion during closure of the binder and thereby assure proper alignment of the impaling prongs with the apertures of the leaves.
2. In a loose leaf binder of the visible record type, wherein the complementary binder heads are connected for relative longitudinal as well as hinged motion so that leaves on the impaling prongs of one binder head may be shifted with respect to leaves on the impaling prongs of the other binder head; cooperating latch parts on said binder heads for releasably securing the binder heads in their closed positions; and cam means on one of said parts positioned to engage the other of said parts and automatically shift the binder heads longitudinally to one limit of relative movement during closure of the binder to assure proper alignment of the impaling prongs with the apertures of the leaves.

ADOLPH G. LOTTER.
